United States Patent Office

Des. 188,469
Patented July 26, 1960

188,469

LUGGAGE LATCH

John B. Humphries, Stamford, Conn., assignor to The
Excelsior Hardware Company, Stamford, Conn.

Continuation of design applications Ser. No. 54,799 and
Ser. No. 54,801, Mar. 2, 1959. This application Apr.
27, 1960, Ser. No. 60,513

Term of patent 14 years

(Cl. D50—7)

Fig. 1

Fig. 3

Fig. 2

Figure 1 is a perspective view of a luggage latch, showing my new design;

Figure 2 is a side view;

Figure 3 is a sectional view of a portion of the latch cover taken along lines 3—3 of Figure 1 and looking in the direction of the arrows;

Figure 4 is a perspective view of a luggage latch showing another embodiment of my new design;

Figure 5 is a side view of the luggage latch shown in Figure 4; and

Figure 6 is a sectional view of a portion of the latch cover taken along lines 6—6 of Figure 4.

This application is a continuation of my applications Serial Nos. D. 54,799 and D. 54,801, both filed March 2, 1959, and both now abandoned.

I claim:

The ornamental design for a luggage latch, substantially as shown and described.
